UNITED STATES PATENT OFFICE.

JOSEPH ARTHUR HENRY HATT, OF BROOKLYN, NEW YORK.

MACHINE FOR MAKING PRINTING-PLATES.

1,302,920.

Specification of Letters Patent.

Patented May 6, 1919.

Application filed June 16, 1916. Serial No. 103,959.

To all whom it may concern:

Be it known that I, JOSEPH ARTHUR HENRY HATT, a citizen of the United States, and a resident of Brooklyn, in the county of Kings and State of New York, have invented certain new and useful Improvements in Machines for Making Printing-Plates, of which the following is a specification.

The invention relates to machines for making planographic printing plates, and more especially to machines for registering, transferring and assembling designs upon such plates.

Objects and advantages of the invention will be set forth hereinafter in part, and in part will be obvious herefrom, the same being realized through the means and combinations pointed out in the appended claims.

20 The invention consists in the novel parts, constructions, arrangements, combinations and improvements herein shown and described.

The accompanying drawings herein referred to, and constituting a part hereof, illustrate one embodiment of the invention, and together with the description, serve to explain the principles thereof.

Of the drawings:

30 Figure 1 is a fragmentary top plan of a machine constructed in accordance with the principles of the invention;

Fig. 2 is a central longitudinal vertical section through the machine of Fig. 1;

35 Fig. 3 is an end elevation, on an enlarged scale, with the shaft in section, of the cylinder shown at the left in Figs. 1 and 2;

Fig. 4 is a fragmentary elevation, looking at Fig. 3 from the right;

40 Fig. 5 is a transverse complete vertical section on the line A—B looking in the direction of the arrows;

Fig. 6 is a transverse vertical section, on an enlarged scale, of the original printing means shown near the center of Figs. 1 and 2, adapted for using a stone;

Fig. 7 is a view similar to Fig. 6 showing the device adapted to use a flexible metal plate;

50 Fig. 8 is a section substantially on the line C—D of Fig. 7;

Fig. 9 is an enlarged fragmentary sectional view showing the manner of registering the cylinder with the original printing means, such as a lithographic stone;

Fig. 10 is a fragmentary view, partly in section of a portion of the positioning and registering mechanisms for the respective printing surfaces;

Fig. 11 is a fragmentary elevation looking at Fig. 10 from the bottom;

Fig. 12 is a fragmentary sectional view on the line E—F of Fig. 2, showing the cylinder lifting and dropping means, the adjustment for the plate bed and associated parts;

Fig. 13 is a fragmentary elevation, partly diagrammatic, of the design registering device;

Fig. 14 is a fragmentary top plan corresponding to a portion of Fig. 13;

Fig. 15 is a fragmentary detail elevation, partly in section, substantially on the line G—H of Fig. 13;

Fig. 16 is an enlarged sectional detail of 75 the plate clamping device located just above it in Fig. 2;

Fig. 17 is a fragmentary elevation on an enlarged scale of a registering device used with certain classes; and

Fig. 18 is a vertical section substantially on the line I—K of Fig. 17.

In said embodied form a general frame structure 1 is provided with longitudinally disposed supporting side frames 2. Upon said frames are means for bringing to registry or position, and maintaining in such registry and position the various printing surfaces, including the original printing means from which the design is transferred, and the final printing plate to which the design is transferred, and a transferring or design conveying device, so that the designs may be positioned as desired upon the final printing plate.

In the embodied form, supported upon the bed of the machine, are means for supporting an original printing means of relatively large size, such as would be used for many kinds of work as will be well understood. As embodied, said means is shown (Fig. 2) adapted to use a lithographic stone 3, which stone is supported upon a bed 4. The bed 4 is adjustable vertically to allow for differences in the thicknesses of various 100 stones and also to vary the pressure between the stone and the transfer cylinder. The embodied form of such adjustment comprises a bed frame 5, carried by the frame members 2, which bed frame 5 has trans-

105

110

verse webs 6. In said bed frame and webs are threaded vertically disposed screw bolts 7, the upper end of the bolts engaging recesses in bosses 8, which bosses are formed 5 on the bottom of the bed or plate 4. By turning the screw bolts 7 one way or the other the bed or plate 4 and the surface of the stone may be accurately brought to the desired level.

10 Means are also provided for accurately positioning the stone both longitudinally and transversely, and in the embodied form thereof, side walls 9 and 10 are fixed to and project upwardly from the bed or plate 4 15 (Figs 1 and 2). In these side walls 9 and 10 are screw threaded, respectively, screw bolts 11 and 12. By turning these screw bolts the printing surface 3 may be accurately brought to desired or registered position 20 both longitudinally and transversely of the machine.

In accordance with certain features of the invention there is provided also a relatively small but widely and accurately movable 25 original printing means, together with devices for giving such wide or varied and accurate movement and positioning thereto, and in conjunction therewith means for bringing the transferring device into accurate registry therewith in its various positions. As embodied, such means comprise 30 a cross frame 20 (Figs. 1, 2, 6, 7, and 8) supported between the longitudinally extending side frames 2, said frame 20 having transversely disposed upwardly extending side walls 21 and 22, which on their inner side serve as guide-ways for the original printing means and its carrier. Mounted to travel transversely of the machine, guided 35 by the members 21 and 22, is the carrier 23 for the original printing means, said carrier having downwardly extending flanges 18 and 19, fitting within and guided by the guide members 21 and 22. The carrier 23 40 for the original printing means is adapted to employ either a lithographic stone or a flexible metal sheet, or other suitable printing surface.

As shown in Figs. 1, 2 and 6, said carrier 45 is adapted for using a stone. Referring more particularly to said figures, the carrier 23 is provided with a supporting surface 24 for the lithographic stone 25. Means are provided for regulating the height or level 50 of the printing surface of the stone 25, and as embodied screw bolts 26 project through outwardly extending rims or flanges upon the carrier 23, and rest upon the tops of the guiding members 21 and 22. Thus the level 55 of the printing surface is nicely regulated and determined, while the carrier 23 and the stone 25 may be moved and positioned as desired, the points of the screw bolts 26 sliding upon the tops of the members 21 and 22 60 as the carrier moves.

Means are likewise provided for regulating and determining the position of the stone 25, and the design thereon relatively to its carrier 23, and as embodied, vertically extending side walls 27 and 28 fixed to, or 65 integral with, the carrier 23 surround the stone 25. In threaded engagement with the walls 27 and 28 are horizontally arranged screw bolts 29, which may be turned to position the printing surface of the stone 25 both 70 longitudinally and transversely as desired.

When a flexible metal plate or like surface is utilized for the original printing means, the carrier therefor is modified accordingly. Details of an embodiment thereof are shown 75 in Figs. 7 and 8, the carrier 23 having its top surface 30 at a height positioned to support the flexible plate in printing position. The vertical height of the carrier may be adjusted as desired, and this may be done as 80 shown in Figs. 5 and 6 with reference to the stone. Suitable means for fastening the plate are employed, and as shown a clamp or clamps 31, extending transversely, hold the plate 32 at one end and a clamp or 85 clamps 33, extending along the other end, hold the opposite side of the plate. A suitable stretching device is shown, comprising a screw bolt 34, rotatably carried by the bracket 35 of clamp 33, the screw bolt being 90 threaded into the carrier 23.

Means are provided for moving and accurately positioning the original printing means and its carrier, and in the embodied form thereof (Figs. 1, 2, 5, 6, 7, 8, 10 and 11) 100 a screw shaft 40 extends across the machine and is journaled in the frame members 2. Threaded on the shaft 40 is a wing nut 41, which nut engages with the printing surface carrier 23 (Figs. 6, 7 and 8), so that when 105 the screw shaft 40 is rotated the nut 41 will travel therealong in either direction moving the printing means carrier 23 therewith.

Means are provided for minutely and accurately determining the position of the carrier 23 through the rotations of the shaft 40. As embodied, the shaft 40 (Figs. 10 and 11) has fixed thereto a pinion 42, which pinion meshes with a gear 43, which gear is carried on a short shaft 44 extending through 110 and journaled in the frame member 2. On its exterior end the shaft 44 has a squared end 45 to take a crank 46. Around the exterior end of the shaft 44 is a dial 47 fastened by screws 48 to the frame 2. On this dial are a circular series of subdivisions of an inch, and fixed to shaft 44 is a finger or pointer 48, which, as the shaft 45 is rotated, passes over the fractional sub-division of the dial. As illustrated, each revolution 115 of shaft 44 equals an inch of travel for the printing means carrier 23, and any fraction of an inch or travel desired will be indicated by the finger 48.

Means are provided in connection with the 120

- original printing means carrier, for bringing the conveying or transferring surface into register therewith, and in the embodied form thereof longitudinally of the tops of the members 27 of the stone carrier, and in a corresponding position in Fig. 7, are arranged guides 49, which co-operate with the conveying or transferring cylinder in a manner hereinafter to be described.
- 10 Means are provided for supporting and positioning the final printing plate to receive the designs in their various desired and predetermined positions, the embodied form thereof cooperating with means for effecting the desired changes in relative longitudinal position between the original printing means and the final printing plate, which latter means co-operate also with the means for effecting transverse relative changes of position between them, which in the present embodiment are applied to the original printing means as just described.

The support for the final printing plate is shown (Figs. 1, 2 and 12) adapted to use a flexible metal printing plate. As embodied a bed 60, upon which the printing plate is supported, is mounted on the machine frame to travel longitudinally of the machine. Clamps 59 of suitable form are provided for holding the final printing plate in position upon bed 60. The clamps are shown pivoted at 57 and spring-pressed in closed position by springs 58. The supporting means therefor (Figs. 2, 5 and 12) comprise supporting ledges or tracks 61 carried at either side of the machine upon the longitudinally extending frame members 2.

In the preferred form, the bed 60 is carried upon roller bearings 62, resting upon the ledges or tracks 61.

Means are provided for accurately positioning vertically the surface of the final printing plate carried upon the bed 60 for the printing impressions, and in the embodied form thereof, screw bolts 63 are threaded in bosses 64 on the two frame members 2, the ends of said screw bolts fitting into recesses on the under side of the ledges or trackways 61, so that the ledges or trackways 61 and therewith the bed 60 may be vertically accurately positioned as desired. Bolts 65 pass through slots formed in the lower part of the trackway 61, said bolts being threaded into the frame members 2 to hold the trackways 61 in position while permitting of their being raised and lowered as desired.

In the embodied form of means for longitudinally traveling and positioning the support for the final printing plate, there is formed upon the under, longitudinally extending side edges of the bed 60 (Figs. 1, 2 and 12) and upon outwardly extending extensions 66, a straight geared rack 67.

66 Meshing with these racks 67 at either side

of the machine are pinions 68, which pinions are fixed to a shaft 69, said shaft 69 extending across the machine, and being journaled in the machine frame. Turning and positioning means for said shaft such as 70 have already been described in connection with the positioning of the original printing means, and which are shown in Figs. 10 and 11, may be provided. Thus the longitudinal position of the bed 60 and its plate may be 75 accurately determined to the minutest desired fraction of an inch. The two positioning means co-operate together to give such a minute and accurate relative movement and positioning or registering in all directions 80 to the original printing means and final printing plate.

There are thus provided co-operating positioning means for producing or effecting with the utmost precision any desired transverse and longitudinal relative movement and positioning of the original printing means and of the finished printing plate, together with proper transferring facilities operating between the two. Thus by the 85 machine of my invention a design or series of designs upon the original printing means may be put down in any degree of duplication at any desired point or place or points or places upon the final printing plate with 90 the greatest facility and precision.

In accordance with one feature of the invention the transferring means comprises a device capable of co-operating both with a large original printing means such as shown 100 at the left in Figs. 1 and 2, and with a small printing means, such as is shown in the center of Figs. 1 and 2 (and having a wide range of movement, as already described) or with either as desired. In accordance 105 with certain features of the invention the transferring means operating between the original printing means and the finished printing plate comprise a cylinder having rotational and translational movement in 110 definite relation to the stone and plate positioning means, whereby the design will be placed upon a final printing plate in accordance with the relative positioning and registering of the various plates and stones. 115

As embodied a cylinder 80 is provided (Figs. 1, 2, 3, 4 and 9) having a shaft 81, said shaft having a squared end 82 which may take a crank wherewith to rotate the cylinder. A curved handle 83 is also fixed 120 to one or both heads of the cylinder to be used in rotating it as desired. Fixed to the heads of the cylinder 80, at or near its ends, are gear rings or gear wheels 84, engaging toothed or geared rack 85, at either side of 125 the machine, supported by and extending along the horizontal frame members 2.

Means are provided by the invention for effecting and for preventing impression contact between the cylinder and the printing 130

surfaces of the original printing means and the final printing plate, said means preferably operating both automatically and also at the will of the operator. In the embodied 5 form thereof (see especially Figs. 2, 5 and 12), extending along the rack bar 85 is a horizontally disposed, vertically movable bar 86, supported by but vertically movable relatively to the frame 2. The vertical 10 movement of the bar 86 is sufficient that when it is depressed the gear rings 84 will roll along the gear racks 85 with the surface of the cylinder 80 in position for printing contact with the stones or plates, but when 15 the bar 86 is in upward position, the cylinder 80 is lifted out of printing contact, while leaving the gear rings 84 still in mesh with the geared racks 85. Coöperating with the bars 86 are bearing rings 87 on the ends 20 of the cylinder 80, the rings rolling along the bars.

The embodied means for causing and controlling the movement of the bars 86 comprise a series of toggles 88, located at 25 either side of the machine and at various points therealong. The upper arm 90 of each toggle is pivotally connected at its upper end 89 to the bar 86. The bottom arm 91 of the respective toggles is pivotally connected at the lower end 92 of the arm, to a shaft 93, said shaft extending across the bed of the machine, and being similarly connected to a toggle on the opposite side of the machine. From the shaft 93 there 30 extends downwardly an arm 94, said arm being pivotally connected to a longitudinally extending bar 95. The bar 95 connects the various toggles which are located along one side of the machine to cause them to move together, and a similar bar 95 connects the various toggles located along the opposite side of the machine. The bars 95 and shafts 93 thus cause all the toggles to move together.

40 Means are provided whereby the cylinder 80 at one end of its path of travel will drop itself for impression, that is, move downwardly into the printing contact position, and at the opposite end of its path of travel 45 will raise itself from impression that is, move upwardly out of the printing contact position, for the return trip. In Figs. 1 and 2 the cylinder would be in impression or in printing contact traveling to the right, 50 and out of impression or out of printing contact traveling to the left in said figures.

In the present embodiment from the shaft 93 which is at the right hand end of the machine (Figs. 1 and 2) extends upwardly 55 a lever or trigger 97, and from the shaft 93 which is at the left hand end of the machine, extends upwardly an arm or trigger 98, these trip arms or triggers being preferably duplicated at each side of the machine. These arms are in position to en-

gage at their upper end with the bearing rings 87 upon the cylinder 80. It will be seen that when the cylinder engages the trips 98, the toggles all along and at both sides of the machine will be broken and the 70 cylinder 80 will be in depressed or printing position. When the cylinder 80 engages the trips 97, all the toggles along and at both sides of the machine will be made, and the bars 86 will be raised to lift the cylinder 80 75 out of printing contact or out of impression position.

The embodied means for throwing on and off the impression at the will of the operator comprise a foot lever 100 (Figs. 2 and 5) 80 fixed intermediately its ends to one end of a shaft 101. Shaft 101 extends across the machine and is journaled in the machine frame. There is a foot lever 100 at each end of shaft 101, at either side of the machine. Pivots connected to one arm of the respective levers 100 is an upwardly extending rod 103, which rod at its upper end is pivotally connected to an arm 104, the two arms being fixed to the ends of one of 90 the cross shafts 93. The foot pedals at either side of the machine, thus serve to permit an operator to raise or lower the transfer cylinder when and where desired.

In the embodied form the transfer cylinder 95 is provided with offset printing surfaces. Said cylinder in accordance with one feature of the invention has two transfer or carrying surfaces corresponding generally in area to a large and a small original printing means, the small transfer surface, in accordance with one feature of the invention having relative movement, which may be in unison and in register with that of the smaller original printing means.

The larger cylindrical transfer surface is provided with an offset printing surface 110, which may have stretching clamps 111 and 112 of suitable and approved design, and which need not be described in detail.

The other transfer surface is carried upon a portion of the cylinder which, as stated, is movable and positionable along the cylinder and transversely of the machine and in harmony and register with the original printing means 23. In the embodied form, a segment 113 of the cylinder 80 has its under surface beveled to engage with undercut or dovetail trackways or guideways 114 and 115 projecting from and formed along 115 the cylinder 80. If desired, a gib 116 may be used, with suitable tightening screw 117 to produce sufficient pressure to hold the sector 113 in any desired position. Upon the surface of the sector 113 a suitable offset surface is mounted, and preferably a heavy rubber blanket 118 is stretched underneath and thereover a light rubber sheet 119, preferably of a light and soft grade of rubber similar to dental rubber. In the 120 130

embodied form suitable stretching means are provided for each of the offset layers, the stretching means 120 stretching the lower blanket, and the roller 121 with 5 ratchet 122 and pawl 123 serving to stretch the layer of light rubber smoothly there-over.

The embodied form of means for effecting and retaining registry between the 10 original printing means 25 and the segment 113 comprises circumferentially disposed grooves 124 and 125 formed in the ends of the segment 113, and adapted to engage with the guides 49, which are formed 15 on the top of the members 27 of the carrier 23 for the original printing means. Thus if the cylinder 80 be rolled into position, the grooves 124 and 125 will engage the guides 49, and as shaft 40 is turned, the original 20 printing surface 25 and the segment 113 will be moved and registered together. The segment 113 being so registered, it will remain in position. When stone 25 has been inked, the segment will roll thereover and 25 be in register as just described. It will then roll along and print the impression in precise register upon the final printing plate.

Means are provided by the invention for 30 registering the positions upon the original printing means and on the final printing plate with reference to each other, and also for registering the various original printing means properly upon their respective final printing plates, where printing is done in a 35 plurality of colors.

In the embodied form of such means (Figs. 13, 14 and 15), there is provided a pair of gear wheels 140, meshing respectively with the geared tracks 85 at each side 40 of the machine. Gear wheels 140 are connected together by a shaft 141, extending across the machine, each of the gear wheels being inclosed in a housing 142. The housings 142 extend downwardly along the outer 45 side of the bed or frame members 2, and are provided with suitable positioning means, to fix them in position upon the bed. The embodied form thereof comprises spring pins 143 inclosed in casings 144 formed on the housing 142. The pins 143 are acted on, 50 respectively, by springs 145, inclosed within the casings 144, the inner ends 146 of the pins engaging registering holes formed in the bed plate or frame members 2. The pins 55 are retractable by hand and are spring-pressed into engagement with frame members 2. Encircling the shaft 141 is a sleeve 147, having binding screws 148 for fixing it in position upon the shaft. The sleeve 147 is 60 provided at its ends with collars 149 mounted upon and encircling the sleeve 147, and held in position longitudinally thereon by the collars 149, is a sleeve 150, which is thus maintained longitudinally in position while 65 being free to move angularly about sleeve

147 and shaft 141. Formed on the sleeve 150 is an internally threaded boss 151, into which boss is screw-threaded a rod 153. A counter-weight 154 is fixed to the sleeve 150 substantially opposite to the rod 153, which 70 serves to swing upwardly the rod 153 and maintain it in an elevated position when not in use.

Slidably mounted upon the rod 153 is a block 154 having a clamping screw 155 for 75 holding it in position upon the block. A registering finger 156 is slidably mounted in the block 154, and is held in adjusted position by a clamping screw 157. A sliding block 158 is also mounted on the rod 153, and is 80 held in position by clamping screw 159. On an arm 160 extending from the block 158 is a double ended registry finger 161 which is 85 slidably mounted in the arm 160, and is held in position by clamping screw 162.

By the positioning of the fingers 156 and 90 161 along the rod and applying the fingers to the various printing surfaces, any position on one of the printing plates or printing surfaces may be brought into exact registry 95 with any position upon the other. That is, any point or position on the final printing plate and any point or position on the design of the original printing means may be brought into exact registry in advance, so 100 that the offset transfer means which takes the design from the original printing means will place the design accurately in the desired position upon the final printing plate. The double pointer 161 may be utilized also, 105 as indicated in Fig. 13, to test or register the transverse position of the offset cylinder or of any desired position on the surface thereof with the position of any point or part of the design or designs on the printing 110 surface.

Means are provided by the invention for angularly positioning or registering a design on the original printing means with respect to the axis or general disposition of the design as it is to be laid down upon the plate, and also to angularly position or register the different original printing means for the various or successive colors of irregularly placed or positioned designs.

In the embodied form thereof (Figs. 17 and 18) said means is shown applied on to the transversely positionable carrier for the original printing means. Mounted upon the carrier 23 is a base 180, said base being positionable by the screw bolts 29 as already described and as will be clearly understood. Said base 180 is centrally apertured to receive a downwardly extending stub shaft 181, which projects from the bottom of a 120 circular plate 182 resting upon the base 180. Plate 182 is provided preferably around its margin with a circular scale 183 marked off in degrees or other suitable units of circular measure. A fixed pointer 184 is carried 125 180

on the base 180 and coöperates with scale 183 to indicate the rotation of the angular circular plate 182. Upwardly projecting from the plate 182 are a plurality of posts 185 into each of which posts is threaded, respectively, a screw bolt 186. Resting upon the plate 182 is a cylindrical support 187, the sides thereof being engaged by the screw bolts 185, whereby the support 187 may be accurately positioned in all directions horizontally with respect to the plate 182, while the support 187 will be angularly moved with the plate 182. A clamping screw 195 is in threaded engagement with base 180, its point bearing against the stub shaft 181 to hold plate 182 and parts carried thereby in adjusted angular position. Carried upon the support 187 is a printing plate bed 188 provided with plate stretching and clamping means 189. Fixed to the base 180 is a vertically extending post 190. In an aperture in post 190 is carried an arm 191, a clamping screw 192 being threaded in the head of the post 190 and serving to hold the rod 191 in position. In the end of the rod 191 is mounted a registering finger 193 provided with a clamping screw 194.

In printing irregularly arranged designs, as for instance in the printing of envelopes, economy of space requires that they be placed as closely as possible upon the final printing plate. They are therefore arranged at varying angles, as regards the lines or axes of the designs. It is very essential that not only the designs be placed accurately longitudinally and transversely, but also angularly, and it is essential that this angular registration be accurately reproduced on the successive plates for the various colors where the envelopes or other work is printed in multi-color. By the mechanism just described all of these operations and registrations are expeditiously and accurately effected with the completest nicety, whereas heretofore the work has been laboriously and difficultly performed by hand labor which consists in merely trying it out.

One manner of using the mechanism just described is substantially as follows:—

50 The angle of inclination of the design to the longitudinal and transverse lines of the machine is easily determinable, and the angular adjustment or positioning of the plate 196 in Figs. 17 and 18 to the same angle is a simple, mechanically positive, and practically instantaneous operation. The design may be supplied with register marks, carried on the printing plate for one of the colors, or on an impression on paper or other material taken from such a printing plate, such plate being held or clamped in position upon the bed 60. Such marks are equi-distant from a chosen central point of the design, and should be arranged upon the selected axes of the design. By placing the same

marks in the same relation or positions with regard to the design upon the plate 196, and then rotating the design beneath the point 193, the design upon the plate 196 will be in the desired longitudinal and transverse position when all of the registering marks on the plate 196 pass beneath the point 193. The positioning can be effected by rotation of the shaft 40 and of the screw bolts 29. The angular position of the plate 196 is then secured in the manner already described, and upon transferring the design from the plate 196 will go down upon the final printing plate in absolute register both longitudinally, transversely and angularly.

70 The manner of operation of the machine will be clearly understood from the description and statements of operation already given in connection with the various groups of parts of the mechanism. It may be stated 75 in brief résumé as follows:—

The final printing plate is placed upon the bed 60, and where a single design carried upon a small lithographic stone or metal plate or other original printing means is to 90 be put down many times upon the final printing plate in accurately predetermined position, it may be considered that the original printing means 25 may be moved by screw shaft 40, say to the farthest transverse 95 position toward the top of the sheet in Fig. 1. The bed 60 for the final printing plate may be likewise positioned to receive the design at the end of the final printing plate nearest to the original printing means. The 100 devices for accurately positioning these means to any desired fractions of an inch have already been described. The segment 113 of the transverse cylinder was in engagement with the guides 49 during the positioning 105 transversely of the stone 25, and after the inking of the stone, the transverse cylinder is rolled thereover and also over the final printing plate, thereby taking the design from the original printing means and 110 laying it down upon the final printing plate. If there are a plurality of designs in the same transverse alinement, longitudinal movement may be imparted to the bed 60 and thereby to the final printing plate, to 115 bring it accurately into the position for the second design, but the original printing means need not be positioned transversely for this second transfer, nor for any transfers that are in longitudinal alinement along the final 120 printing plate.

When such line of impressions has been laid down upon the final printing plate, and there is another line of designs in like longitudinal alinement, the original printing 125 means may then be moved and positioned transversely once for such entire longitudinal line of designs, and the bed 60 may be moved between each successive offset impression, but in the opposite direction. Thus the 130

printing plate may be filled with designs, which are in accurate registry in each instance, with greatest expedition and ease and with very little registering and positioning of the machine parts.

When a very large design, or a large number of designs are carried upon a single stone or printing surface in a relationship which it is desired to reproduce, such as the stone 10 3, they may be all simultaneously transferred by the cylinder 80 to the final printing plate upon the bed 60. The various positioning and registering devices would be used in this instance to determine different points 15 upon the design or to register the design upon successive plates for use in multi-color printing.

It will be understood that these explanations of the manner of using the machine 20 are illustrative and not restrictive, and that the machine is capable of other widely diversified uses, which will be obvious to those skilled in the art, or may be learned by practical experience with the machine.

25 In addition to the work of transferring described in connection with the statement of operation, the machine can be used for proofing and the pointer devices and different registering mechanisms would enable 30 proofing to be done with more facility and accuracy than can be done in the ordinary way. The machine can also be used for printing small editions, such as any hand press may be used for, and for making duplicate transfer plates at one impression 35 when the first multiple transfer plate has been completed. The idea being to make the first multiple transfer and place that in the area for the large original which comes 40 in contact with the large rubber blanket surface and then make a duplicate transfer of the whole thing in the one operation. It will be understood that the manner of 45 using pointed out is illustrative and not restrictive.

From all the foregoing it will be understood that a machine has been provided realizing the objects and advantages of the invention, and having the capacities herein 50 set forth, and also having other capacities and realizing other objects and advantages. It will be understood that changes may be made from the precise structure herein 55 shown and described without departing from the principles of the invention and without sacrificing its chief advantages.

What I claim as my invention and desire to secure by Letters Patent is:—

60 1. A printing plate making machine including in combination original printing means, a final printing plate, a transfer member, and means for moving said original printing means and said transfer member

together to position them relatively to said final printing plate.

2. A printing plate making machine including in combination original printing means, means having a final printing plate, a transfer member, and means for engaging together one of said means and said transfer member, and means for moving and positioning them relatively to the other means.

3. A printing plate making machine including in combination original printing means, a final printing plate, a transfer member, and means for engaging together said original printing means and said transfer member, and means for moving and positioning them relatively to the final printing plate.

4. A printing plate making machine including in combination a transfer cylinder rolling along a trackway, a cylindrical transfer surface mounted thereon and movable along the cylinder, a movable original printing means, and means for engaging together the original printing means and the transfer surface for joint positioning thereof.

5. A printing plate making machine including in combination a relatively large original printing means, a small original printing means, final printing plate means, and traveling transfer means coöperating with all said means, said small original printing means being positionable transversely, and said final printing plate being positionable longitudinally.

6. A printing plate making machine including in combination a relatively large original printing means, a small original printing means, final printing plate means, and a rolling transfer cylinder coöperating with all said means, said small original printing means being positionable transversely, and said final printing plate being positionable longitudinally.

7. A printing plate making machine including in combination a relatively large original printing means, a small original printing means, final printing plate means, and traveling transfer means coöperating with all said means, said small original printing means being positionable transversely, said final printing plate being positionable longitudinally, and a transfer surface on said cylinder being movable with said small original printing means.

In testimony whereof, I have signed my name to this specification, in the presence of two subscribing witnesses.

JOSEPH AETHUR HENRY HATT.
